UNITED STATES PATENT OFFICE.

CLEO M. PEASE, OF BROOKLYN, NEW YORK.

DESIGN FOR A BOX.

No. 39,802.

Specification for Design.

Patented Feb. 2, 1909.

Application filed August 31, 1908. Serial No. 451,121. Term of patent 3½ years.

To all whom it may concern:

Be it known that I, CLEO M. PEASE, a citizen of the United States, residing at 338 Bridge street, Brooklyn, in the county of Kings and State of New York, have invented a new, original, and ornamental Design for a Box, of which the following is a specification, reference being had to the accompanying drawing, forming a part thereof.

The figure shows a perspective view of the design.

I claim:

The ornamental design for a box as shown.

CLEO M. PEASE.

Witnesses:

M. M. DEITSCH,

M. M. GRADY.
